(57) **CLAIM**

The ornamental design for a mixer control interface, as shown and described.

DESCRIPTION

FIG. 1 is a perspective view of a mixer control interface showing our new design;

FIG. 2 is a front elevation view of FIG. 1;

FIG. 3 is a left elevation view of FIG. 1;

FIG. 4 is a right elevation view of FIG. 1;

FIG. 5 is a top view of FIG. 1;

FIG. 6 is a perspective view of a second embodiment of the mixer control interface;

FIG. 7 is a front elevation view of FIG. 6;

FIG. 8 is a left elevation view of FIG. 6;

FIG. 9 is a right elevation view of FIG. 6; and,

FIG. 10 is a top view of FIG. 6.

The broken lines shown in FIGS. 1-10 are for illustrative purposes only and form no part of the claimed design.
